CLAIM

The ornamental design of a folded floor exercise mat, substantially as shown and described.

DESCRIPTION

FIG. 1 is a front elevation view of a folded floor exercise mat showing my new design;

FIG. 2 is a side elevation view thereof; the opposite side being a mirror image; and

FIG. 3 is a top and front perspective view thereof.

The bottom and rear portions of the exercise mat are substantially plain and unornamented.

FIG. 1

FIG. 3
